UNITED STATES PATENT OFFICE.

CLIFFORD A. HARRIS, OF BRYAN, TEXAS, ASSIGNOR, BY MESNE ASSIGNMENTS, TO THE AUTOMATIC ELECTRIC SHOE POLISHING MACHINE COMPANY, OF BRYAN, TEXAS, A CORPORATION OF TEXAS.

SHOE-POLISHING MACHINE.

Application filed February 26, 1921. Serial No. 447,953.

To all whom it may concern:

Be it known that I, CLIFFORD A. HARRIS, a citizen of the United States, residing at Bryan, in the county of Brazos and State of 5 Texas, have invented a certain new and useful Improvement in Shoe-Polishing Machines, of which the following is a full, clear, and exact description, reference being had to the accompanying drawings.

10 This invention relates to apparatus for cleaning and polishing shoes, and is particularly concerned with means for applying paste to the shoes, and thereafter for causing other means to polish the shoes.

15 An object of my invention is to provide a simple machine having separate sets of paste applying and polishing brushes, together with means for causing the shoes to be alternately acted upon, by such brushes, 20 whereby a high degree of polish may be secured with the usual paste.

Another object is to co-ordinate the above mentioned means with the mechanism for 25 rotating the brushes, and to enable the paste applying and the polishing operations to be effected without requiring a person to move from his chair during the entire operation.

Other objects include the provision of 30 means for automatically controlling the cleaning, paste-applying, and polishing operations upon the deposit of a coin, as well as the provision of means for releasing such coin, and stopping the motor when the polishing operation is completed.

35 In accomplishing the above objects, I provide two sets of brushes, one for cleaning and applying paste to the shoes, and one for thereafter polishing the shoes. In the preferred embodiment of my invention I employ a reciprocating carriage on which the brushes are mounted, and I employ means for moving the shoe rests from the path of the paste applying brushes into the path of the polishing brushes.

40 The means for accomplishing the above objects will be more fully set forth in the following description, which relates to the drawings, and the essential characteristics will be set forth in the claims.

45 In the drawings Fig. 1 is a longitudinal

section partly in elevation of a shoe polishing machine, embodying the features of my invention; Fig. 2 is a transverse section showing an elevation of the brushes; Fig. 3 is a plan of the mechanism employed for 55 elevating the foot rests; Fig. 4 is an elevation of such mechanism shown in Fig. 3; Fig. 5 is a section taken through the control mechanism; Fig. 6 is an enlarged elevation of the ratchet control mechanism; Fig. 7 is a fragmentary view illustrating an adjustable 60 ratchet wheel.

My invention contemplates the employment of at least two sets of brushes, which are adapted to act upon the shoes entirely 65 independently of each other, while the customer or person whose shoes are to be cleaned, remains seated in one position. In the drawings, I have shown my invention as embodied in a shoe polishing machine of the 70 reciprocating carriage type, wherein the brushes are rotatably mounted upon the carriage, and I have shown means for moving the shoes from the path of one set of brushes into the path of another set of brushes, while 75 the carriage is reciprocating.

In Fig. 1 such a machine may be contained within the housing 10, on which a chair 11 and foot rests 12 are supported. Within the housing I provide a motor 13 80 which drives the shaft 14, and is suitably geared so as to reciprocate the carriage 15. The means for reciprocating the carriage comprises preferably a Scotch-yoke motion operated from the worm wheel shaft 16 near 85 the center of the carriage. In connection with the paste feeding mechanism, I prefer to employ a plunger contained within the cylinder 17, and adapted to be operated by the control mechanism shown in 90 general at 18. The above described mechanism represents, in general, the structure shown in the drawings, but a more thorough description of such mechanism is set forth in my co-pending application, Serial No. 428,991, filed December 7, 1920.

To support the paste applying and polishing brushes upon the carriage 15, I provide standards 19, which are preferably in 100

the form of castings which are rigidly secured to the top of the carriage. These standards are shown as provided with arms 20 for supporting the shafts 21 on which 5 shafts the paste applying brushes 22 are mounted. These paste applying brushes are on the extreme forward end of the carriage; and are arranged to be the first brushes which have contact with the shoes 10 during the cleaning operation.

The shoes to be cleaned are so positioned that each shoe is intermediate two of the vertical brushes 22, which brushes are adapted to clean the sides and rear of the 15 shoes. To clean the toes and upper front part of the shoes, I provide horizontally arranged brushes 23, which are supported on the shaft 24, which shaft may be supported on brackets 25, which are rigidly secured to 20 the standards 19. As the carriage reciprocates, the brushes 22 are rotated from the shaft 14 by bevel gearing, which transmit horizontal rotation of the shaft 26 to vertical rotation of the shafts 21. To rotate 25 the horizontal brushes 23, I may provide a chain and sprocket gearing, as at 27, and 28, for transmitting rotation in a horizontal plane from the shaft 26, to the shaft 29, and thence to the shaft 24.

30 The brushes heretofore described comprise a unit known as the cleaning or paste applying set, and I will now describe the operation of the brushes comprising the polishing unit. In Fig. 2 it will be seen that 35 the brushes 30 and 31, positioned above the brushes 22 and 23 are in vertical alignment with the cleaning brushes. The brushes 30 are supported in shafts 32, which shafts may be carried in the brackets 33 and may 40 be rotated by chain sprocket gearing 34, driven from the shaft 21. The brushes 30 serve to polish the sides and back of each shoe, while the brushes 31 are adapted to 45 polish the toes.

45 The toe polishing brushes are shown as supported on the horizontally disposed shaft 40, the ends of which are carried in a bearing block 41 mounted on the brackets 33. These brushes may be rotated by a sprocket 50 chain connection 42, which is operated by the horizontal shaft 24. It will be seen, therefore, that the vertical brushes are rotated as a unit, and that the horizontal brushes are rotated as a unit.

55 To support the shoes during the cleaning and polishing operations, I provide the foot rests or pads 12 which may be mounted on the shafts 45 and 46. These shafts as shown in Fig. 3 extend across the machine, and are 60 connected at the ends thereof to the links 47-48 respectively. These links are pivoted preferably at 49 and 50, respectively, to a portion of the frame 67, which is rigid with the housing 10. The mechanism, em-

bodying the links and shafts, comprises a 65 four-bar linkage, which enables the pads 12 to be elevated while remaining at all times parallel to the original position.

As shown in Fig. 4, the arm 51 is rigidly connected with the pivot shaft 49, which shaft is rigidly connected with the link 47. The links 47 and 48 receive an oscillating motion by rotation of the crank arm 52, mounted on the crank shaft 53. A connecting rod 54 extends from the crank arm 52, to the arm 51 and serves to transmit rotary motion of the crank arm to oscillatory motion on the arm 51. In Fig. 4 the dotted line position shows the pads when the crank arm 52 is in the position 75 represented by the dotted lines 84.

To rotate the crank shaft 53, I provide a pinion 55 on such shaft, which is adapted to be rotated by a gear 56, which may be supported on the shaft 57. The gear 56 as 80 shown in Fig. 5 is rigid with the sleeve 58 of the ratchet wheel 59, which wheel may be loosely mounted on the shaft 57.

Referring now to Figs. 5 and 6, it will be seen that the pawl 60, pivoted at 61, to 90 the arm 62, is adapted to engage the teeth in the ratchet wheel 59, and to be held thereagainst by the spring 63. The arm 62 is shown as loosely mounted on the sleeve 58, and is normally held in position by the 95 spring 64, which may be connected to the arm 65 on one of the brackets 66, such brackets being rigidly mounted on the frames 67 which is rigid with the housing 10.

Referring now to Figs. 1 and 3, it will be 100 seen that the pawl 67 supported at 68, on the carriage 15, is arranged to engage the teeth in the ratchet wheel 69 when the carriage approaches the end of its rearward stroke. The ratchet wheel 69 as shown in 105 Fig. 5 may be loosely mounted on the sleeve 58, and may have teeth of such length that the ratchet is rotated one notch on each stroke of the carriage. The tooth 70 on the pawl 67 has sufficient width to engage the 110 ratchet wheel 69, together with the arm 62 adjacent the wheel. The length of the arm 62 and the depth of the teeth in the wheel 69, however, are so related that the pawl 67 normally engages only the teeth and rotates 115 the pawl.

To move the arm 62, I provide two teeth 71, on the wheel 69, which are deeper than the remaining teeth. When the wheel has been rotated so that the tooth of the pawl 120 67 engages one of the deep teeth 71, then the lowermost portion of the arm 62 will be engaged by the pawl and be moved simultaneously with the wheel. When the arm 62 is oscillated, the ratchet wheel 59 is 125 rotated by reason of the fact that the pawl 60 is normally held in engagement therewith. Rotation of the ratchet wheel 59

causes the gear 56 to be rotated, to elevate or lower the foot rest through the linkage heretofore described.

In the particular embodiment shown in 5 the drawing, the ratchet wheel 69 has twelve teeth and I have so positioned the ratchet mechanism that the pawl 67' moves this ratchet wheel $\frac{1}{12}$ of a revolution when it reaches the end of its rearward stroke. 10 It follows, therefore, that the gear 56 is rotated $\frac{1}{12}$ of a revolution, when the pawl 67' engages the tooth 71 in the ratchet 69. The ratio between the gear 56 and pinion 55 is such that $\frac{1}{12}$ of a revolution on the 15 gear causes half of a revolution of the pinion 55. Half of a revolution of the pinion 55 rotates the crank arm 52 from the position shown in the full lines in Fig. 4 to the position shown in the dotted lines. 20 When the crank arm is rotated, as described, then the foot rests 12, being connected to the arm by the four-bar linkage, are transferred from the path of the 25 paste feeding brushes to the path of the shoe polishing brushes, such position being shown in dotted lines, Figs. 1 and 4.

The control ratchet mechanism is shown as so arranged that the foot rests 12 remain in the path of the paste applying 30 brushes for six complete reciprocations of the carriage, while the ratchet wheel 69 is rotated one-half of a revolution. When the carriage reaches the end of the sixth stroke, the pawl engages one of the deep cut 35 notches 71 in the ratchet wheel 69, whereupon further rearward motion of the carriage causes the mechanism heretofore described to be operated and the foot rests 12 to be moved. The carriage again reciprocates six times until the pawl again 40 engages another deep cut tooth 71, there being preferably two of such teeth on the wheel 69, whereupon the crank arm 52 is again rotated half a revolution, and the foot 45 rests are brought back to their normal position. Consequent upon the return of the foot rests to normal position the mechanism shown in general at 18 is arranged to release a coin and thereby stop the operation 50 of the motor.

The operation of the machine is as follows:—

Assuming that an operator is seated on the chair 11 and the foot rests are in the 55 lowermost position, as shown in the full lines in Fig. 1, then a coin is inserted in the coin chute 75, whereupon the motor 13 is set in operation. When the motor is started, rotation is transmitted through the 60 shaft 14 to the shaft 16 and the carriage is started on the forward motion. At the same time the brushes 22 and 23, 30 and 31 are set in operation. The control mechanism is preferably so arranged that the 65 cleaning brushes 22 pass back and forth

across the shoes once or twice before the paste applying mechanism is operated to apply paste to the brushes 22, such mechanism being operated while the carriage is being reciprocated.

During the reciprocation of the carriage for the paste applying operation, the pawl 67' has been engaging the teeth on the ratchet 69, which teeth have been of such depth that the nose of the pawl is prevented 70 from engaging the arm 62. After the paste has been applied and a dull polish produced on the shoes, then the control ratchet is so arranged that a deep cut tooth 71 is engaged by the pawl 67', whereupon the arm 62 is 75 oscillated with the ratchet wheel 69. When the arm 62 is oscillated, toward the rear of the machine, then the ratchet wheel 59 is rotated by the pawl 60 and the gear 56 being rigid with the wheel 59 is also rotated. 80 A rotary motion of the gear 56 is then transmitted to the crank arm 52 through the pinion 55. Since the ratio between the pinion and gear is one to six, then when the gear is rotated one-twelfth of a revolution, 85 the crank arm is rotated one-half a revolution. Rotary motion of the crank arm is then transmitted through the connecting rod 54, arm 51 and links 47-48 to the foot rest 12. The length of the crank arm 52, and the 90 arm 51, is such that the foot rests are elevated from the path of the paste applying brushes to the path of the polishing brushes, it being understood that the elevating action 95 takes place while the ratchet wheel 69 is being moved the distance of one tooth. When the foot rests are in the elevated position, the crank is on a dead center, so that downward pressure by the customer would not depress the foot rests.

After the foot rests are elevated, the carriage continues to reciprocate, while the pawl 67' engages the teeth in the ratchet wheel 69, which teeth being of such depth that the pawl 67' clears the lowermost portion of the arm 62. The polishing operation is then continued until another deep cut tooth 71 is engaged by the pawl 67', whereupon the foot rests are returned to the original position. The mechanism 18 is then 105 arranged to release the coin and to shut off the motor 13, whereupon the machine is ready for another customer.

The two deep teeth 71 are shown in Fig. 6, as diametrically opposite each other, with the result that half of the operation is performed by the paste-applying brushes and half by the polishing brushes. However, the deep notches may, if desired, be otherwise positioned, so that one set of brushes 110 operates for a major fraction of a cycle and the other set for a minor fraction. If desired, this allotting of the cycle may be adjustable; for instance, all of the teeth may be cut deep enough to allow the pawl 67' to 115 120 125 130

engage the arm 62, but those which are not to have such operation may be partially filled by removable blocks of shims 75, Fig. 7, held in place by screws 76.

5 From the foregoing description it will be seen that I have provided a machine for cleaning and polishing shoes, which provides separate sets of cleaning and polishing brushes, together with means for controlling 10 the operation thereof, whereby the shoes are caused to be acted upon by the paste applying brushes and thereafter by the polishing brushes without requiring the customer to move from his seat. Advantages of such 15 a machine are that ordinary paste may be employed and a high degree of polish may be obtained, since the polishing brushes are not subjected to the application of the paste. Furthermore, it will be seen that I have provided a mechanism for presenting the shoes 20 to alternate sets of brushes, which mechanism is positive in operation, and is adapted to be co-ordinated with the mechanism for controlling the operation of the entire machine.

25 Having thus described my invention, I claim:

1. A shoe polishing machine having in combination paste applying brushes, polishing brushes, a movable carriage therefor, vertically movable foot-rests, means for causing the operation of the paste applying brushes on a shoe and means actuated by contact with the carriage for thereafter 30 shifting said rests, and causing the operation of the polishing brushes on such shoe.

2. A shoe polishing machine having in combination a paste applying brush, means for automatically supplying paste thereto, a 40 polishing brush, a reciprocating carriage for all the brushes, means for causing the operation of the paste applying brush on a shoe, and means for thereafter causing the operation of the polishing brush on a shoe, 45 while the carriage is at the rearward end of its stroke.

3. A shoe polishing machine having in combination a foot rest, a paste applying brush, a polishing brush, a movable carriage for all the brushes, and means associated 50 with the carriage for moving said rest with a rectilinear motion to change the shoe from one brush to the other.

4. A shoe polishing machine having in combination a set of rotary paste applying brushes, a set of rotary polishing brushes, a reciprocating carriage therefor, shoe rests, and means actuated by the carriage for elevating the rests from the path of one of said 60 sets into the path of the other of said sets of brushes.

5. In a shoe polishing machine, the combination of paste applying brushes, polishing brushes disposed thereabove, means for simultaneously reciprocating and rotating

said brushes, shoe rests, and means for moving the rests from the path of the paste applying brushes and into the path of the polishing brushes.

6. A shoe polishing machine having in combination shoe rests, paste applying brushes, polishing brushes, means for actuating said brushes, and ratchet means for moving said rests relative to the brushes.

7. A shoe polishing machine having in combination a set of paste applying brushes, a set of polishing brushes, a reciprocating carriage supporting the brushes, one of said sets being disposed above the other set, shoe rests, and means for moving said rests from the path of one of said sets and into the path of the other set of brushes.

8. A shoe polishing machine having in combination foot-rests a set of paste-applying brushes and a set of polishing brushes, 35 each of said sets comprising vertically and horizontally disposed brushes, a carriage for supporting all of said brushes and means actuated by said carriage for transposing said rests from the path of one set of 40 brushes into the path of another set of brushes.

9. In a shoe polishing machine, the combination with foot-rests, of paste-applying brushes and polishing brushes, means for operating the brushes, an index wheel, means for advancing said wheel step by step, and other means connecting the wheel with the foot-rests, whereby rotation of said 50 wheel shifts said rests from the paste-applying brushes to the polishing brushes, and vice versa.

10. In a shoe polishing machine having in combination, foot rests, paste-applying brushes, means for supplying paste thereto, 105 polishing brushes, a carriage supporting all of said brushes, and means controlled by the carriage for moving the foot rests relatively to the brushes.

11. In a shoe polishing machine having in combination, foot rests, paste-applying brushes, polishing brushes, a carriage supporting all of said brushes and ratchet means controlled by the carriage for moving the foot rests relatively to the brushes.

12. In a shoe polishing machine, the combination with two sets of brushes, of means for rotating them, movable foot-rests, an index wheel, and means whereby the wheel transposes said rests from one set of brushes 120 to another set.

13. In a shoe polishing machine, the combination with two sets of brushes, of means for rotating them, movable foot-rests, a ratchet wheel, and means whereby the depth 125 of the ratchet wheel teeth actuates said rests, to shift them from one set of brushes to another.

14. In a shoe polishing machine, the combination of a foot-rest a paste applying 130

- brush, a polishing brush, means for reciprocating said brushes, shoe rests, means for moving said rests and for causing a shoe on the rest to be acted on by the paste applying brush and subsequently by the polishing brush and means for adjusting the period of action of each brush.
15. In a shoe polishing machine, the combination with movable foot rests, of a ratchet wheel, and means whereby the effective depth of the teeth on said ratchet wheel controls the operation of said rests.
16. A shoe polishing machine having in combination, foot rests, a reciprocating carriage, rotary brushes thereon, a ratchet wheel operable by said carriage, and means connecting the ratchet wheel with the foot-rests whereby rotation of said wheel causes the rest to be elevated.
20. 17. A shoe polishing machine having in combination, foot rests, a reciprocating carriage, brushes thereon, an index wheel adapted to be rotated a certain fraction of revolution for each reciprocation of the carriage, and means controlled by said wheel for elevating said rests.
25. 18. A shoe polishing machine having in combination, foot rests, a reciprocating carriage, brushes thereon, a member adapted to be rotated a certain fraction of a revolution for each reciprocation of the carriage, and means controlled by said member for raising and lowering said rests.
30. 19. A shoe polishing machine having in combination, foot rests, brushes, a reciprocating carriage for said brushes, an index wheel, means for rotating said wheel when the carriage reaches the end of its stroke, and ratchet means adapted to be operated by said index wheel for moving said foot-rests.
35. 20. A shoe polishing machine having in combination, foot-rest, a ratchet wheel, a member adjacent the wheel and rotatable independently thereof, means for rotating said wheel and simultaneously operating said member, and other means connecting said member with the foot rests, whereby rotation of said member causes movement of said foot-rests.
40. 21. A shoe polishing machine having in combination foot-rests, brushes, a carriage therefor, a ratchet wheel, a member associated with the wheel, and rotatable independently thereof, a pawl carried by the carriage and adapted to rotate said ratchet wheel and member, and means connecting said member with the foot-rests, whereby rotation of the member causes movement of said foot-rests.
45. 22. A shoe polishing machine having in combination, foot-rests, an index wheel, a member associated with said wheel, means for operating the wheel a certain fraction of a revolution at periodic intervals, and other means for causing said wheel and member to be simultaneously rotated during one of said intervals, said last mentioned means being connected with the foot-rests whereby rotation of said member shifts the 70 foot-rests.
50. 23. A shoe polishing machine having in combination, foot-rests, an index wheel, brushes, a carriage adapted to support all of said brushes, means for turning said index wheel when the carriage reciprocates, and means connecting the wheel with the foot-rest, whereby rotary motion of the wheel is transformed into rectilinear motion of the rests.
55. 24. A shoe polishing machine having in combination, foot-rests, a reciprocating carriage, brushes mounted on said carriage, a ratchet wheel, means for rotating the wheel by reciprocation of the carriage, a second ratchet wheel rotatable independently of said first mentioned wheel, means for causing one of said ratchet wheels to move the other of said wheels, and means connecting one of said ratchet wheels with the foot- 80 rests.
60. 25. A shoe polishing machine having in combination, foot-rests, two ratchet wheels rotatable independently of each other, means for intermittently engaging the two wheels, 95 means connecting the foot-rests with one of said wheels, whereby rotary motion of the wheel is transformed into vertical motion of the foot-rests.
65. 26. In a shoe polishing machine the combination with foot-rests, of two ratchet wheels rotatable independently of each other, an oscillatable member intermittently engaging said wheels, means connecting the foot-rests with said member whereby the 100 foot-rests are shifted simultaneously with the oscillation of said member.
70. 27. A shoe polishing machine having in combination, foot-rests, two ratchet wheels, means for intermittently rotating one of said wheels, an oscillatable arm intermediate said wheels, and a pawl carried by the arm and adapted to engage one of said wheels, said means being operable for simultaneously engaging the other of said wheels and the arm, 110 whereby rotation of one wheel causes rotation of the other, and links connecting said last named wheel with the foot-rests.
75. 28. A shoe polishing machine having in combination, foot-rests, brushes, a reciprocating carriage therefor, means for rotating said brushes, an index wheel adapted to be moved a fraction of a revolution for each stroke of the carriage, a second wheel adapted to be rotated at predetermined intervals simultaneously with the first mentioned wheel, and means connecting the second wheel with foot-rests whereby rotation of the second wheel causes the foot-rests to shift from one position to another. 115
80. 29. A shoe polishing machine having in combination, foot-rests, brushes, a reciprocating carriage therefor, means for rotating said brushes, an index wheel adapted to be moved a fraction of a revolution for each stroke of the carriage, a second wheel adapted to be rotated at predetermined intervals simultaneously with the first mentioned wheel, and means connecting the second wheel with foot-rests whereby rotation of the second wheel causes the foot-rests to shift from one position to another. 120
85. 30. A shoe polishing machine having in combination, foot-rests, brushes, a reciprocating carriage therefor, means for rotating said brushes, an index wheel adapted to be moved a fraction of a revolution for each stroke of the carriage, a second wheel adapted to be rotated at predetermined intervals simultaneously with the first mentioned wheel, and means connecting the second wheel with foot-rests whereby rotation of the second wheel causes the foot-rests to shift from one position to another. 125
90. 31. A shoe polishing machine having in combination, foot-rests, brushes, a reciprocating carriage therefor, means for rotating said brushes, an index wheel adapted to be moved a fraction of a revolution for each stroke of the carriage, a second wheel adapted to be rotated at predetermined intervals simultaneously with the first mentioned wheel, and means connecting the second wheel with foot-rests whereby rotation of the second wheel causes the foot-rests to shift from one position to another. 130

29. A shoe polishing machine having in combination two sets of brushes, a foot-rest, an index wheel, means for operating said brushes, other means for advancing said wheel step by step and a linkage connecting said wheel with the foot-rests, whereby rotation of said wheel shifts the foot-rests from one position to another.

30. In a shoe polishing machine, the combination with foot rests, of an index wheel,

means for advancing said wheel step by step and a four-bar linkage connecting said wheel with the foot-rests, whereby rotation of said wheel shifts the foot-rests from one position to another.

In testimony whereof, I hereunto affix my signature.

CLIFFORD A. HARRIS.
